DRYING MACHINE CONVEYER AND
TRANSFER MECHANISM

Leo G. Kenney, Chicago, Ill.

Application January 3, 1951, Serial No. 204,195

8 Claims. (Cl. 198—84)

1

This invention relates to drying machines and is more particularly concerned with the provision of a machine suitable for use in drying inks, lacquers, paints, enamels, glues, varnishes and the like, when applied to various materials, such as paper, fiberboard, metal, glass, fabric and wood.

While the drying machine hereinafter described is adapted for use in drying various types of materials, it is particularly designed and constructed for use in drying printing mediums applied to sheet material by stencil printing machines of the type disclosed in Patent No. 2,398,379 in which a squeegee acts to force a printing medium, such as ink or paint, through a screen stencil onto the sheet material to be printed.

After a stencil printing operation, it has heretofore been the practice to mount the printed sheets upon drying racks or endless conveyors with infra-red lamps disposed to dry the printed sheets. In the use of endless drying conveyors, it has been found necessary to employ a conveyor approximately 90 feet in length to handle the production of one stencil printing machine. It will thus be appreciated that a relatively large proportion of the floor space of a printing plant is devoted to drying conveyors or racks. The present invention contemplates the provision of a relatively small drying machine designed to correspond in size with and to handle the output of a stencil printing machine of the type disclosed in the aforesaid patent, thereby making it possible to install several stencil printing machines and machine dryers in the space heretofore occupied by drying racks and conveyors.

This invention further contemplates the provision of a drying machine mounted within an insulated cabinet in which the temperature, humidity and movement of the sheets are controlled to gradually dry the printing medium without distorting the sheets, and then to automatically stack the dried sheets at room temperature. In the use of other types of equipment heretofore employed in drying printed stencil sheets, a considerable amount of time and labor was required to rack and unrack the sheets. It is also well known that the sheets were subjected to dust and dirt entrained in the air and were often distorted or otherwise damaged due to slow drying conditions, methods of handling, etc.

This invention further contemplates the provision of a drying machine embodying a plurality of infra-red lamps disposed to direct infra-red rays against the printed sheets, the intensity of the rays being controlled to suit the type of printing medium impressed upon the sheets.

2

This invention further contemplates the provision of a drying machine including a housing in which the printed sheets are first directed through a drying space and thence through a vapor space to relax the dried sheets prior to stacking same.

This invention further contemplates the provision of a drying machine embodying a shuttle mechanism operable to move the sheets back and forth between two stacks of shelves disposed in staggered relation whereby the sheets are progressively transferred step-by-step from the top shelves toward the bottom shelves and thence onto a stacking platform.

This invention embodies other novel features, details of construction and arrangement of parts which are hereinafter set forth in the specification and claims, and illustrated in the accompanying drawings, wherein:

Fig. 1 is a side elevational view, partly in section, illustrating a drying machine embodying features of the present invention.

Fig. 2 is a sectional view taken along the line 2—2 of Fig. 1.

Fig. 3 is an enlarged fragmentary sectional view taken along the line 3—3 of Fig. 2.

Fig. 4 is a transverse sectional view taken along the line 4—4 of Fig. 3.

Figs. 5 and 6 are schematic longitudinal sectional views illustrating the manner in which the printed sheets are progressively transferred step-by-step from the upper shelves toward the lower shelves.

Fig. 7 is a detail perspective view illustrating a pivot finger provided on the shuttle mechanism for engagement with printed sheet material disposed upon the loading shelf.

Fig. 8 is a schematic view illustrating the clutch mechanism in its disengaged position.

Fig. 9 is a schematic view illustrating the clutch mechanism in its engaged position.

Referring now to the drawings for a better understanding of the present invention, the drying machine is shown as comprising a rectangular base 2 which is preferably formed of structural steel such as angle iron to support a pair of front corner posts 3—3 and a pair of rear corner posts 4—4. A pair of transverse frame members 3a and 4a are secured to the upper ends of the corner posts 3—3 and 4—4, respectively, to support a pair of top tracks 5—5 disposed in a common plane and in spaced parallel relation. A pair of lower tracks 6—6 are secured at their ends to the front and rear corner posts 3—3 and 4—4 and are disposed in spaced parallel rela-

tion with respect to the top tracks and each other.

A carriage, indicated generally at 7, is mounted for reciprocative movement along the tracks 5—5 and 6—6 and is shown as comprising a pair of side frames 8—8 secured in spaced parallel relation by means of cross frames 9 and 10 and angle plates 11—11, the several parts being preferably secured together by means of bolts or rivets. Each side frame 8 is provided with two sets of rollers 12—12 and 13—13 for rolling engagement against opposite sides of its adjacent top track 5. Connecting plates 14—14 are secured at their upper ends to their respective side frames 8—8, and each plate is secured at its lower end to a roller mounting member 16. Each member 16 supports two sets of rollers 17—17 and 18—18 for rolling engagement along opposite sides of its adjacent lower track 6.

A front push rod support 19 and a rear push rod support 21 are arranged in spaced parallel relation transversely of the carriage 7 and are secured at their ends to the roller mounting members 16—16 by means of bolts 22. A plurality of vertically disposed front push rods 23 are secured intermediate their ends to the front support 19, and a plurality of vertically disposed rear push rods 24 are secured intermediate their ends to the rear support 21. The push rods 23 and 24 are preferably mounted within apertures formed in their respective supports 19 and 21 and adjustably engaged by means of set screws 26. A finger 25 is pivotally mounted upon the upper end of each front push rod 23, as illustrated in Fig. 7.

A front shelving 27 is shown as comprising a pair of shelf supports 28—28 secured at their lower ends to the base 2 and projecting upwardly in spaced parallel relation to support a plurality of shelves 29 disposed in horizontal planes and spaced one above the other. Each shelf 29 preferably comprises a plurality of supporting fingers 31 secured in spaced parallel relation along a finger support 32 which, in turn, is secured at its ends to the shelf supports 28—28.

A rear shelving 33, similar in construction to the front shelving 27, is shown as comprising a pair of shelf supports 34—34 secured at their lower ends to the base 2 and projecting upwardly in spaced parallel relation to engage and support a plurality of shelves 36 disposed horizontally in spaced parallel relation and one above the other. Each shelf 36 comprises a plurality of fingers 37 secured to finger supports 38 which, in turn, are secured to the shelf supports 34—34. By referring to Figs. 1, 3, 5 and 6 in the drawings, it will be observed that the front shelving 27 faces toward the rear shelving 33 and that the latter faces toward the front shelving. It will also be noted that the front shelves 29 are disposed in staggered relation with respect to the rear shelves 36.

A pair of transverse frame members 41—41 are secured at their ends to the corner posts 3—3 and 4—4, respectively, to support therebetween a pair of longitudinally extending guide supports 42—42. A guide member 43 is mounted on each support 42 by means of brackets 44, the guides being disposed in spaced parallel relation to initially guide a sheet of printed material S into and through the machine.

To convey sheets of printed material S into the machine, a pair of arms 46 are secured at one of their ends to the carriage cross frame 9 and are connected at their other ends to a relatively thin

angle-shape member 47 which is adapted to slide along a feed platform 48 secured to the transverse frame member 3a.

A pair of sprocket chains 51—51 are mounted on driving sprockets 52—52 and driven sprockets 53—53 journaled in bearings 54—54 and 56—56, respectively. The bearings 54—54 and 56—56 are mounted upon the longitudinally extending guide supports 42—42. Drive pins 57—57 are secured to the sprocket chains 51—51 for pivotal engagement with one of the ends of connecting links 58—58 which are pivotally connected at their other ends to the carriage 7. The driving sprockets 52—52 are keyed to a driving shaft 59 having a conventional clutch mechanism 61 mounted thereon. The clutch mechanism 61 is provided with a driven pulley 62 to receive a belt 63 which extends around a driving pulley 64 of a conventional power transmission unit 66. A motor 67 acts through a driving pulley 68, a belt 69 and a driven pulley 71 to transmit power through the power transmission unit 66 to the driving pulley 64. The clutch mechanism 61 may be of any conventional type embodying a clutch sleeve 71 movable axially of the shaft 59 to cause a clutch mechanism to frictionally engage and disengage the shaft 59.

The clutch sleeve 71 is pivotally connected to one of the ends of a pair of links 72 which have their other ends pivotally connected at 73 to a toggle link 74 pivotally connected at 76 to the adjacent top track 5. A connecting link 77 is pivotally connected at 73 to the links 72 and 74 and is also pivotally connected at 78 to a lever 79 journaled at 81 on the adjacent guide support 42. A connecting link 82 is pivotally connected at one of its ends to the lever 79 and is pivotally connected at its other end to a foot pedal 83 mounted for pivotal movement at 84 on the base 2. A connecting link 86 is pivotally connected at 78 to the lever 79 and is also pivotally connected at 87 to a rocker arm 88 supported for pivotal movement on a bracket 89 secured to the transverse frame member 3a. A push rod 91 is mounted upon the carriage 7 for engagement with the free end of the rocker arm 88 during movement of the carriage 7 in one direction.

The machine is enclosed within an insulated housing 92 comprising a top 93, side walls 94—94, a front wall 96 and a back wall 97. Doors 98 and 99 are provided in a side wall 94 and the back wall 97 to permit access to the interior of the housing. If desired, a plate glass window 101 may be provided on one of the side walls 94 to permit visual inspection of parts within the interior of the housing. A plurality of infra-red lamps 102 are supported on the top wall 93 of the housing 92 to direct infra-red rays downwardly toward the shelves 36. The infra-red lamps 102 are preferably mounted within a socket housing 103 provided with openings at 104 for the passage of heated air from the interior of the housing 92. A water tank 106 is supported upon the base 2 of the machine.

In the operation of the drying machine thus shown and described, stencil printed sheets are delivered directly from a stencil printing machine to the drying machine to dry the ink, paint or other printing medium applied to the sheets. The printed sheets are placed upon the platform 48 and are drawn into the machine by the angle-shape transverse member 47 engaged to the ends of the arms 46—46, as illustrated in Fig. 5 of the drawings. During return movement of the carriage 7, the printed sheet S is dropped onto the

top shelf 29 of the stack of shelves 27. When the carriage 7 moves to the right, as illustrated in Fig. 5, the fingers 25 on the push rods 23 engage the rearward edge of the sheet S to move the latter from the upper shelf 29 onto the uppermost shelf 36 of the stack of shelves 33. On the return stroke of the carriage 7 the push rods 24-24 act to move the printed sheet S from the uppermost shelf 36 onto the second shelf in the stack of shelves 27 as illustrated in Fig. 6. By referring to Figs. 5 and 6 in the drawings, it will be noted that the printed sheets S are shuttled back and forth between the shelves in the two stacks of shelves 27 and 33 until the sheets are delivered in stacked relation onto a stacking platform 110 provided on the base 2.

The machine is preferably operated through a clutch control mechanism manually operable to initiate movement of the carriage 7 and having means for automatically stopping the movement of the carriage 7 after each cycle of operation of the carriage 7. As illustrated schematically in Figs. 8 and 9 in the drawings, the operator pivots the foot pedal 83 which acts through the connecting link 82, lever 79, connecting link 77, toggle link 74 and connecting link 72 to engage the clutch 71 and thus cause the motor 67 to turn the driving shaft 59. The carriage 7 is thus caused to move to the right, as illustrated in Fig. 1, and thence to the left. During the return movement of the carriage 7 the stop arm 91 provided on the carriage 7 acts to pivot the lever 88 which acts through the connecting links 86 and 77, toggle link 74 and connecting link 72 to disengage the clutch 71 to stop rotational movement of the drive shaft 59 and movements of the carriage 7. It is apparent, however, that the stop arm 91 on the carriage 7 could be removed or moved out of operative position to permit the carriage 7 to operate continuously until manually stopped by the operator.

As the printed sheets S are shuttled back and forth between the two stacks of shelves 27 and 33, the rays and/or heat from the infra-red lamps 102 act to dry the printing medium on the sheets without causing distortion of same. To further maintain the printed sheets in a relaxed flat condition, a reservoir 106 filled with water is provided on the base 2 to add moisture to the air within the cabinet 92 during operation of the machine. When the printed sheets have been deposited in stacked relation upon the stacking platform 110, the printing medium on the sheets is thoroughly dried and the sheets are ready for delivery to the customer.

While this invention has been shown in but one form, it is obvious to those skilled in the art that it is not so limited but is susceptible of various changes and modifications without departing from the spirit and scope of the claimed invention.

I claim as my invention:

1. In a machine for drying articles, two fixed stacks of shelves, adjacent sides of said stacks being spaced apart and arranged face-to-face, the shelves of one stack being disposed in staggered relation with respect to the shelves of the other stack, and means including interconnected sets of push rods extending vertically through their respective stacks of shelves to move articles back and forth between the two stacks of shelves to cause the articles to descend through the machine.

2. In a machine for drying articles, a structure supported for horizontal reciprocative

movement and including two interconnected sets of vertically disposed push rods to move articles back and forth within the machine, and means including a plurality of fixed stacks of shelves, adjacent sides of said stacks being spaced apart, the shelves of adjacent stacks being disposed in staggered relationship to direct articles from an upper level within the machine to a lower level responsive to reciprocative movement of said structure.

3. In a machine for drying articles, a pair of interconnected vertically disposed pushers spaced apart and supported for reciprocative movement to alternately engage and move articles back and forth within the machine, and two stacks of article supporting shelves arranged in fixed spaced relationship, adjacent sides of the stacks being spaced apart to define a vertical passageway therebetween, the shelves of one stack being staggered with respect to the shelves of the other stack to direct the articles from an upper level within the machine to a lower level responsive to reciprocative movement of said pushers.

4. In a machine for drying articles, two fixed stacks of shelves, adjacent sides of said stacks being spaced apart and arranged face-to-face, the shelves of one stack being disposed in staggered relation with respect to the shelves of the other stack, means to push articles back and forth between the two stacks of shelves, said means including a carriage, and two pushing elements depending from said carriage and through their respective stack of shelves to alternately engage an article.

5. In a machine for drying articles, two fixed stacks of shelves, adjacent sides of said stacks being spaced apart and arranged face-to-face, the shelves of one stack being disposed in staggered relation with respect to the shelves of the other stack, a structure to push articles back and forth between the two stacks of shelves, said structure including a carriage mounted for reciprocative movement, two pushing elements depending from said carriage and through their respective stack of shelves to alternately engage opposite ends of an article, and means to drive said structure.

6. In a machine for drying articles, two fixed stacks of shelves, adjacent sides of said stacks being spaced apart and arranged face-to-face, the shelves of one stack being disposed in staggered relation with respect to the shelves of the other stack, a horizontally disposed track, a carriage mounted on said track and including two interconnected sets of pushers to alternately engage and push articles back and forth between the two stacks of shelves, each set of pushers extending vertically through its related stack of shelves, means to actuate said carriage, and means operable to stop the carriage after each cycle of operation.

7. In a machine for drying articles, two fixed stacks of shelves adjacent sides of said stacks being spaced apart and arranged face-to-face, the shelves of one stack being disposed in staggered relation with respect to the shelves of the other stack, means to push articles back and forth between the two stacks of shelves, said means including a carriage, and two pushing elements depending from said carriage and through their respective stack of shelves to alternately engage an article, and means secured on said carriage to engage and deliver an article to be dried onto the uppermost shelf of one of said stacks for engagement by said pushing elements.

8. In a machine for drying articles, two fixed

stacks of shelves adjacent sides of said stacks being spaced apart and arranged face-to-face, the shelves of one stack being disposed in staggered relation with respect to the shelves of the other stack, means to push articles back and forth between the two stacks of shelves, said means including a carriage, tracks to support and guide said carriage, and two pushing elements depending from said carriage, and through their respective stack of shelves to alternately engage an article, and means secured on said carriage to engage and deliver an article to be dried onto the uppermost shelf of one of said stacks for engagement by said pushing elements.
